UNITED STATES PATENT OFFICE.

JOHN FISHER TAYLOR, OF WEST PARK, NEW YORK.

DOOR-BOLT.

SPECIFICATION forming part of Letters Patent No. 322,211, dated July 14, 1885.

Application filed April 1, 1885. (No model.)

To all whom it may concern:

Be it known that I, JOHN FISHER TAYLOR, of West Park, in the county of Ulster and State of New York, have invented a new and 5 Improved Door-Bolt, of which the following is a full, clear, and exact description.

The object of my invention is to provide a simple, inexpensive, effective, and durable bolt, which while fastening a door or like object will hold or bind it closely to its casing or seat, and without regard to the variations in size of the door or casing caused by changes in temperature or the weather.

The invention consists in a door-bolt made 15 with a bar adapted to slide and to be turned axially, and having a cam or eccentric lug, and held to the door so its lug may enter a recess or pass behind a shoulder for holding the bar projected into the eye of a catch-plate fixed to 20 the door-casing, together with a spring held so as to offer resistance to the cam-lug as the bolt-bar is turned axially after it has been shot into the catch, all as hereinafter fully described and claimed.

Reference is to be had to the accompanying 25 drawings, forming part of this specification, in which similar letters of reference indicate corresponding parts in all the figures.

Figure 1 is a face view of parts of a door and 30 its jamb or casing, with my improved bolt in its preferred form applied. Fig. 2 is an end view of the bolt with the spring-case in section, and an edge view of part of the door. Fig. 3 is a horizontal sectional elevation of the door, its 35 jamb, and the bolt. Fig. 4 is a face view of the bolt-catch. Fig. 5 is a front view illustrating a modified construction of the bolt-bar support and a separate spring-case, and Fig. 6 is an inside view of the spring-case shown 40 in Fig. 5.

Referring first to Figs. 1 to 4, inclusive, of the drawings, the letter A indicates the locking-bar of the bolt. B is a plate used in the preferred form of the bolt, and C is the catch 45 of the bolt. The bar A is fitted loosely in an eye or bearing, b, formed on or fixed to the plate B, and has a lever-handle, D, projecting about at a right angle from it near its forward end, a, which is adapted to enter the eye c of 50 catch C. At the forward end of plate B, preferably, is formed a box-like chamber or case,

E, and a slot, b', in the front of the plate allows the cam or eccentric lug F, which is fixed to the bolt-bar A about at a right angle with its lever-handle D, to enter the case E, so that when the handle D is operated after the end a of bar A is entered within the eye c of plate C the lug F will pass through slot b' to hold the bar A projected and will enter case E, and the end or toe of the cam-lug F will press against a spring, G, contained in case E, so that the door H will be forced closely against the jamb or casing I as the contact-point of the lug F passes beyond a line drawn through the center of the bolt-bar A, as shown in Fig. 2, in which position the lever D will be locked by the spring. The spring G offers sufficient resistance to the cam-lug F to force the end a of bar A to the outer part of the eye c of catch C, and hold the door firmly against the rabbit or shoulder i of the casing I, so as to prevent drafts entering around the closed door, and also prevent rattling of the door, and the spring yields more or less to the pressure of cam-lug F should the wood of the door or its casing shrink or swell by changes in temperature or the weather; hence the door will always be closed tightly to the casing by the bolt.

The spring against which cam-lug F acts may have various forms; but for economy in construction and adjustment I prefer to make the spring of a metal plate bent into a form, so that it may be held in place by hanging it on one of the fastening-screws J, which pass through the case E into the edge of the door to hold the forward end of the bolt to the door, the other end of the bolt being held to the door by screws K, passed through plate B into the face of the door. Should the spring be fixed to the back of plate B, the back wall, e, of the case E, against which wall one limb of the spring G (shown) is forced by cam-lug F, may be dispensed with; hence the case E is not essential to the successful working of the bolt. To unbolt the door, it only is necessary to swing lever D to withdraw cam-lug F from slot b', as in dotted lines in Fig. 2, and the bolt-bar A then may be slid back clear of catch C, and so as to be supported by the eye b of plate B, which plate may have more than one eye b to support the bar A, if desired. I

make the catch C with its eye *c* formed at one angle of a dovetail-shaped plate, *c'*, as in Fig. 4, so that when the plate is let into the side of the rabbet of the door-casing I, its shape will 5 of itself offer the necessary resistance to pressure tending to burst the door open from the outside, and little or no strain will be brought upon the screws *c'*, passed through holes *c'* into the casing.

As shown in Figs. 5 and 6, the plate B may be dispensed with, and a small plate, B', having an eye, *b*, to support the bolt-bar A, may be fastened to the door H by screws *k*, and the spring-case then will be made in a separate piece, as at E', and will be fitted over a recess cut in the edge of the door. The case E' has a couple of lugs, *e' e'*, to hold the spring G in place against the inward pressure on it of the cam-lug F of the bolt-bar A, the said lugs *e'* substituting the back wall, *e*, of case E, and the case E' is to be held to the door H by screws J, on one of which the spring G may be held, substantially as above described. A plate-spring may of course be fixed to one of the face-flanges *e'* of case E' to receive the back-pressure of the cam-lug F of the bolt-bar, as will readily be understood.

It is obvious that the bolt is very simple in construction, inexpensive to make and put in place, and is positive in action and effective and durable in use.

The bolt may be used upon doors, sash, blinds, or other objects requiring a fastening such as the bolt affords.

Having thus described my invention, what I claim as new, and desire to secure by Letters Patent, is—

1. A door-bolt comprising a locking-bar supported to slide in an eye adapted for at-

tachment to the door, and said bar provided 40 with a lever or equivalent means for turning it axially, and also with a cam-lug adapted to lock behind a stop or shoulder on the door to hold the bolt projected, and a spring arranged to offer resistance to the cam-lug as the bolt is 45 turned axially, substantially as herein set forth.

2. The combination, in a door-bolt, of a bar, A, provided with a lever, D, or equivalent means for turning it axially, and having a 50 cam-lug, F, a plate, B, having an eye, *b*, to support bar A, and a slot at *b'* for the passage of lug F, and a spring supported by and back of the plate B, so as to offer resistance to the cam when the bar A is entered into the catch-plate and turned, substantially as herein set forth. 55

3. The combination, in a door-bolt, of a bar, A, provided with a lever, D, or equivalent means for turning it axially, and having a 60 cam-lug, F, a plate, B, having an eye, *b*, to support bar A, and a slot, *b'*, for the passage of lug F, and said plate having a case, E, at its outer end, and a spring, G, made in $\textcircled{1}$ form and held within case E, so as to offer resistance to the lug F when the bar A is entered into the catch-plate and turned, substantially as herein set forth. 65

4. As an improved article of manufacture, a catch for a door-bolt made with its bolt-bar-receiving eye formed on a dovetail-shaped plate adapted to be let into the casing, substantially as herein set forth. 70

JOHN FISHER TAYLOR.
